UNITED STATES PATENT OFFICE

LOUIS DUNKELBERG, OF NEW YORK, N. Y.

GOLF TEE

Application filed June 4, 1926. Serial No. 113,626.

This invention relates to devices for supporting golf balls in position to be struck in driving from a teeing ground or other places where the ball is allowably arranged upon the support in position to be driven, such devices being known as "tees".

Tees for supporting the ball are usually made by compressing a bit of earth or sand into the desired form and size. It has also 10 been proposed to turn tees from wood, a cup for the ball being provided at one end while from the base of the cup extends a centrally located cone-shaped extension for insertion in the earth. In driving at the ball the tee 15 is quite apt to be struck and knocked for some distance, often becoming concealed in the grass. In order that the tee may become readily seen and located, the wooden ones referred to have been painted in conspicuous colors so 20 as to be readily discernible.

The wooden tees referred to are liable to be chipped, broken and rendered useless by being struck by the golf clubs in swinging at the ball and the paint soon becomes chipped 25 and worn off.

According to the present invention these objections are avoided while all of the advantages are realized.

One object of the invention is to provide a 30 tee wherein the head has one or more prongs for insertion in the ground, attached to it at offcenter point or points. The device may then be conveniently grasped by placing one finger below the head and one above it in placing the device in position.

A further object of the invention is to mold the tee of suitable material. This provides not only an accurate and inexpensive method of manufacture, but also affords opportunity of adding coloring matter to the 40 material before it is molded so that it will be diffused throughout the mass of the material and cannot be chipped off as in the case of paint as above referred to. When 45 this structure of tee is employed it will re-

main of the desired coloring so long as the tee exists. It is preferred to use celluloid as the material of the tee, as this lends itself readily to the molding and coloring operation and has the desired physical characteristics to give the best results in the completed tee. 50

Other and ancillary objects of the invention will appear hereinafter.

In the accompanying drawings which illustrate the invention— 55

Fig. 1 is a perspective view of the improved tee; and

Fig. 2 is a vertical section of the tee showing it in position in the ground and also a ball mounted upon it. 60

Referring to the drawings, the tee comprises a head shown in this case as a disk 1 having a concavity 2 in its upper face, for receiving the golf ball. From the edge of the disk 1 extends the prong 3 adapted to be inserted in the ground to secure the tee in position. By having the prong off-center, it is possible to employ the disk as a sort of handle, placing the forefinger beneath the 65 disk and the ball of the thumb in the concavity at the top of the disk. Of course this could not be done unless the prong were moved to one side out of the way. While it is believed to be most advantageous to employ one prong as shown in the drawing, it is obvious that if desired a number of prongs greater than one might be employed. 70

The tee just described is preferably formed of molded celluloid, the desired color being 80 imparted by mixing this color in the material at or before the molding operation so that it permeates substantially the whole mass.

The tee having been made as described it 85 may be inserted in the ground 4 as shown in Fig. 2 and the golf ball 5 placed in position thereon as shown in Fig. 2.

While the invention has been illustrated in what is considered its best application it may 90

have other embodiments without departing from its spirit and is not therefore limited to the structure shown in the drawings.

What I claim is:

5 A molded golf tee composed of flat celluloid of substantially uniform thickness including a disk shaped head having top concavity, a triangular shaped prong at an angle of less than 90° with said head and joined to said head by a bent portion arranged with a curvature from a continuation of the material of a side of said head into the plane of said prong.

10 15 In testimony whereof I have signed this specification this 3rd day of June, 1926.

LOUIS DUNKELSBERG.
